UNITED STATES PATENT OFFICE.

JOSEPH DUFFY, OF VICTORIA PARK, LONDON, ENGLAND.

WOOD-PAVING.

No. 829,002.

Specification of Letters Patent.

Patented Aug. 21, 1906.

Application filed January 28, 1906. Serial No. 297,446.

To all whom it may concern:

Be it known that I, JOSEPH DUFFY, flooring and paving contractor, a subject of the King of Great Britain and Ireland, residing 5 at Gainsborough Road, Victoria Park, N. E., in the county of London, England, have invented certain new and useful Improvements in Wood-Paving, of which the following is a specification.

This invention has reference to the type of wood-paving wherein individual blocks therefor are made up of an aggregation of a number of separate sections or slices each of which has the form of a rectangular parallelopiped. Then when a sufficient number 15 of these separate portions have been assembled together to make the desired length and width of paving-block to be laid the aggregated sections are secured together, so as to 20 form the complete block.

The object of the invention and the essential feature thereof is to effect the locking together of the component portions of the completed blocks in a much more effective and at 25 the same time more economical manner than that hitherto effected.

The accompanying drawings illustrate the improved construction of composite wood paving-block forming the salient features of 30 my invention.

Figure 1 is a plan view with the block inverted, and Fig. 2 a cross-section. Fig. 3 is a side elevation, and Fig. 4 a longitudinal section, of a block. Fig. 5 is a cross-section of a 35 slight modification of block. Fig. 6 is a side elevation, and Fig. 7 an inverted plan, of a block used in connection with the grouting of the paving-blocks after being laid.

The separate sections or slices *a* forming 40 the completed block have formed in their bases one or more saw-cuts, by preference two, such as *b b*, which pass upward to a predetermined height, being preferably inclined in opposite directions. These saw-cuts are 45 in corresponding positions in each section, so as to lie in a straight line when the sections are put together. Then when the requisite number of separate pieces to form a complete block have been assembled together a 50 locking or bonding bar or strip *b'*, of hard wood or metal or other suitable material of a length equal to that of the block, is forced into each of the saw-cuts or slots, the locking-bar being of the requisite gage, section, 55 and configuration to insure the necessary

amount of side friction and rigidity to effectually lock the whole together.

The locking or bonding bars are preferably arranged so that they project at one end of the block and fall short of the other end to an equal amount, as at *c c'*, Figs. 3 and 4. When placed in position, such composite blocks will be to a certain extent tied to one another by the locking-bars, which will thus serve the double purpose of uniting the component parts of the blocks and assisting in holding the said blocks in place.

I am aware that in connection with wood-block flooring and parquet-flooring it has been previously proposed to obviate the necessity for preparing a special foundation of asphalt or bitumen by employing wood panels or squares having waterproof backings and that it has also been proposed to form the under surface of the flooring panel or square with grooves in which are secured tongues, which also enter and are secured in corresponding grooves formed in the said waterproof backing, the object being that when laid as a flooring moisture shall be prevented penetrating from below, and also to allow the flooring panels or squares being washed without fear of the flooring bulging or becoming uneven, owing to the swelling of the wood.

I am also aware that in connection with wood-paving the blocks for which consist of a plurality of sections or slices it has been proposed to secure the separate pieces together by forming a groove along each side of the block, within each of which grooves is inserted and driven a flat steel or like "dog" having a spike at each end and also one or more between these end spikes.

Figs. 6 and 7 have reference to the means used for the grouting of the paving-blocks after being laid. It is at present the usual practice after laying the blocks to flood the surface of the paving with plastic grout, the object being to fill all joints and render them waterproof. With a view therefore to thoroughly insure the accomplishment of this the slots or grooves *d* of any desired shape are formed in the sides or ends of the blocks or in some cases of the sections or slices of which the blocks are made up. These slots or grooves serve as ducts or conduits for conveying and storing the plastic grout. By this provision a thoroughly water-tight junction and uniform surface is secured, and joints

which would probably open if any shrinkage took place are maintained water-tight.

In Fig. 5 the saw-cuts *b* are formed at angles in a reverse direction to those shown in Fig. 2.

Having now fully described the nature of my said invention, what I claim, and desire to secure by Letters Patent, is—

In wood-paving the combination of a plurality of slices or segments of blocks joined together to form separate sections, saw-cuts

formed at an angle with the base of same and passing upward thereinto; and, bonding or locking bars fitting tightly in the said saw-cuts.

In witness whereof I have hereunto set my hand in the presence of two witnesses.

JOSEPH DUFFY.
